SUPPORTING MOLDING FOR PRICE TAGS AND THE LIKE

Philip Hopp, New York, N.Y., assignor to The Hopp
Press, Inc., New York, N.Y., a corporation of New York

Filed Sept. 30, 1960, Ser. No. 62,327

Term of patent 14 years

(Cl. D1—3)

FIG. 1

FIG. 3

Fig. 1 is a front elevational view of a supporting molding for price tags and the like showing my new design;

Fig. 2 is an edge view thereof; and

Fig. 3 is a rear view thereof.

I claim:

The ornamental design for a supporting molding for price tags and the like, as shown.
